UNITED STATES PATENT OFFICE.

FRANKLIN W. KREMER, OF AKRON, OHIO.

EXHIBITION APPARATUS.

SPECIFICATION forming part of Letters Patent No. 728,246, dated May 19, 1903.

Application filed September 24, 1902. Serial No. 124,682. (No model.)

To all whom it may concern:

Be it known that I, FRANKLIN W. KREMER, a citizen of the United States, residing at Akron, in the county of Summit and State of Ohio, have invented a certain new and useful Improvement in Exhibition Apparatus, of which the following is a complete specification.

My invention has a relation to improvements in that class of devices provided for spectacular exhibitions for public amusement; and the object of my invention is to produce a new and improved device of the class named.

15 To the accomplishment of the aforesaid object my invention consists in the peculiar and novel construction, arrangement, and combination of parts hereinafter described and then specifically pointed out in the claims, 20 reference being had to the accompanying drawings, which form a part of this specification.

In the accompanying drawings, in which similar reference-numerals indicate like parts 25 in the different figures; Figure 1 is an elevation of the fixed portion of my apparatus with two of the balls, hereinafter described, in connection therewith; and Fig. 2, a section of the track and ball on a greatly-enlarged 30 scale, the ball being in central section.

Referring to the figures, 1 is a metallic track consisting of parallel tubes 2, united at intervals by cross-rods 3, which are curved to avoid contact with the ball, to be described.

35 One end of this track starts at an elevated platform 4, whence it projects outward and thence is curved to an inclined length to the floor 5, whence it bends spirally with a gradually-decreasing diameter until it terminates 40 at a horizontal platform or landing 6. The inclined portion of this track is supported at intervals by rods 7, strengthened and steadied by cross-bracing 8. The spiral portion is cross-braced, as indicated, and also braced to the

45 foundations of the different curves by braces 9; but the number and arrangement of these braces will depend upon the size and weight of the track, the number and diameter of its different convolutions, and other conditions 50 that will obtain in different variations of the apparatus. The gage of the track will preferably be twenty-eight inches; but this may

be varied with the taste or needs of the user or as experience may determine is safest and most effective. The car to run on this track 55 is a hollow ball 10, having in some part of its periphery an opening by which it may be entered, closed by a door 11, hung by hinges 12 and arranged to be locked by an inner bolt 13. Supported centrally within the ball 60 10 is an axial rod 14, on which are journaled oppositely-disposed parallel bars 15, united at one end by a cross-bar 16, the opposite ends rising to form hand-grips for the occupant of the car, and on the cross-bar 16 is a 65 seat 17, also for the occupant. The exhibitor ascends to the platform 4 by a stair 18, where he enters the ball and closes and secures the door and seats himself on the seat 17, grasping the upper end of the bars 15 70 to steady himself. The ball is then pushed onto the inclined portion of the track, in the descent of which it acquires such momentum as to follow the first ascent of the spiral portion of the track, and thus successively acquiring momentum by descending the spirals at one side to enable it to ascend and follow the others by centrifugal force until the ball passes from the last spiral onto the platform 75 6, where its progress is arrested by upturned ends of the track, as shown in the drawings, or by other means to prevent shock to the occupant. The occupant then unlocks the door and emerges onto the stage 6, whence he can descend to the floor by a stair.

I do not intend by this description to limit the convolutions of the track to a tapering spiral, as the convolutions may have the same diameter, but to present this as a preferred form of construction.

Having thus described my invention, what I claim, and desire to secure by Letters Patent, is—

1. An improved exhibition apparatus consisting of a spiral two-rail track with a substantially horizontal axis, of equal gage throughout to receive a spherical car, with landings at either end, and means for communicating an initial velocity to the car, substantially as shown and described.

2. An improved exhibition apparatus consisting of a spiral, two-rail track to receive a spherical car with a substantially horizontal axis, of equal gage throughout, the diameters

of the convolutions of the spiral gradually decreasing toward one end; with landings at either end, and means for communicating an initial velocity to the car, substantially as shown and described.

3. An improved exhibition apparatus consisting of a spiral two-rail track with a substantially horizontal axis of equal gage throughout, with one terminal extended upward at a slight inclination from a perpendicular, and the other terminal in a horizontal plane, said track being arranged to receive a spherical car, substantially as shown and described.

15 4. An improved exhibition apparatus consisting of a spiral two-rail track of equal gage throughout, with a substantially horizontal axis, to receive a spherical car, one of the terminals of said track extended at a slight 20 inclination from a perpendicular, with a platform at its upper terminal, and a second platform at its opposite terminal, with means for arresting the momentum of the car at the latter platform, substantially as shown and 25 described.

5. An improved exhibition apparatus consisting of a spiral two-rail track of equal gage throughout with a substantially horizontal axis, to receive a spherical car, the convolutions of the spiral gradually decreasing toward one end, the terminal of said track at its greatest diameter extended at a slight 30 inclination from a perpendicular with a platform at its upper terminal, and a landing at 35 its opposite terminal, substantially as shown and described.

6. An improved car for exhibition purposes, consisting of a hollow sphere with a diametric cross-bar having pivotally mounted thereon two arms extended above and below it, with a seat between the oppositely-disposed ends of said arm, and the other ends conformed to form convenient handles for the hands to grasp, and a door by which said car can be entered, substantially as shown 45 and described.

7. The herein-described exhibition apparatus consisting of a spiral two-rail track of even gage throughout, the convolutions of said spiral gradually decreasing in diameter 50 from one end, with an extension at one end slightly inclined from a perpendicular to a platform; the opposite end terminating at a landing with means for arresting the momentum of the car, in combination with a 55 car consisting of a hollow sphere with a diametric cross-bar and two arms pivotally mounted thereon extending above and below said bar, a seat between the oppositely-disposed ends of said bars, the opposite ends of 60 said bars being molded to form convenient handles for the hands, and a door by which said car may be entered, all constructed and arranged substantially as shown and described and for the purpose specified. 65

In testimony that I claim the above I hereinunto set my hand in the presence of two subscribing witnesses.

FRANKLIN W. KREMER.
In presence of—
C. A. CASTOR,
ARTHUR YERRICK.
